Patented Jan. 4, 1921.

UNITED STATES PATENT OFFICE.

EVAN B. HILLMAN, OF LOS ANGELES, CALIFORNIA.

CONCRETE-FORM FOR REINFORCED HOLLOW WALLS.

1,364,372.

Specification of Letters Patent.

Patented Jan. 4, 1921.

Application filed March 4, 1920. Serial No. 363,178.

To all whom it may concern:

Be it known that I, EVAN B. HILLMAN, a citizen of the United States, residing at Los Angeles, in the county of Los Angeles and State of California, have invented new and useful Improvements in Concrete-Forms for Reinforced Hollow Walls, of which the following is a specification.

This invention relates to apparatus for constructing hollow reinforced walls of cement, and has for its object to provide a device that is simple in construction and in method of readjusting for continuous use in the erection of a building; and in which the parts are substantial and durable and capable of long use, and further an object is to provide an apparatus of the kind that provides for the continuous erection of a cementitious wall with the requirement of apparatus of least weight and with the least requirement of false work practicable in the construction of concrete walls. The invention consists of the construction, the combination and in details and arrangements of the parts, an embodiment of which invention is illustrated in the accompanying drawings and described and claimed herein.

Figure 1 is a side elevation of a wall in course of construction with the device applied thereto.

Fig. 2 is a transverse section on line 2—2 of Fig. 1 on a somewhat larger scale.

Fig. 3 is a plan view of a portion of the wall and a portion of the mold panels thereon showing means for facilitating the placing of reinforcing means.

Fig. 4 is a detail elevational and partial sectional view of the automatic clamp for suspending the mold structure in course of operation.

Fig. 5 is a plan view in partial section of a form of the device.

The apparatus comprises readily shiftable mold forming members and supports therefor and means for tamping the cementitious material as it is continuously poured into the chambers formed by the mold members, and while the apparatus is shown in the present case as used in the construction of hollow walls it may equally as well be adapted for the construction of a mold wall or partition.

In use a series of substantially vertical columns or jack posts 2—2 are arranged in suitable alinement these being pitched in appropriate distance according to the work

in hand, and as illustrated the posts are set in a common plane in the erection of a wall structure having outer and inner walls O and I between which is formed a space S to 60 secure finally a hollow wall that may be reinforced as by transverse braces or ties T.

On each of the jack posts 2 is slidably mounted a traveler or scaffold frame 3 including a central sleeve 4 provided adjacent its lower end with a lug 5 on which is pivoted a link 6 extending upwardly and connected to the outer end of a lever 7 having at its inner end a clamp ring or biting member 8 slidably fitting on its respective post 2 70 with the result that when the weight of the traveling sleeve or carrier 4 is transmitted through the link 6 to the lever 7 the tendency of the ring 8 to tilt about the axis of the column 2 causes the ring to instantly 75 and securely bite on to the surface of the column or post 2 and this will efficiently support the slide or carrier 4 at any desired position on the post.

Mounted on the upper end of the tubular 80 runner 4 is a hub portion 3^a of the frame 3, this hub having outwardly extending arms 10 on the outer ends of which are provided downwardly extending leg portions 11, these being of suitable strength and length 85 and having secured to their inner lower faces panels or sheets of material forming mold boards or sections 12, these boards being of any suitable length and preferably connected to sets or pairs of respective scaffold arms or legs 11 as shown in Fig. 1.

Inwardly opposite to the pendent legs 11 are intermediate downwardly extending legs 13 disposed adjacent to the sides of the tubular runner 4 and the outer faces of the legs 13 are provided with respective mold forming panels or boards 14, these being spaced from the opposite and respective outer mold boards or panels 12 as determined by the desired thickness of the wall. Therefore the scaffold structure forms, when complete, two sets of mold members 12 and 14 each of which forms a chamber to be filled with concrete in the usual manner in the erection of a concrete wall. The upper ends of the outer mold members 12—12 may be outwardly deflected at 12^a to form hoppers or receivers for the plastic material wall. The inner walls 14—14 are extended upwardly to prevent the wasting of the cement into 110 the chamber or space S between the mold panels 13—13.

One of the important features of the present invention is to provide means for effectually and continuously tamping the concrete fill in the mold chambers and also to provide means that may be utilized as elevating jacks to progressively lift the scaffold and mold means as the filling of the mold chambers proceeds. To that end the arms 10 of the scaffold-frame are each shown as provided with bearings 15 through which are guided tamper rods 16 the lower ends of which are provided with tamper bars 17. The tamper rods 16 extend upwardly above the frame 3 and are connected to a cross head 18 having a bearing or collar 19 freely sliding on a respective jack post 2.

Connected to the tamper cross head of each frame 3 is a link 20 the lower end of which is pivotally connected at 21 to a lever arm 22 fulcrumed at 23 on the top of the frame 3. The lever arm 22 has an actuating arm 24 extending beyond the fulcrum 23 and this arm may be actuated manually or mechanically so as to rock the lever arm 22 in the direction of the arrow thereon so as to thrust the tamper rods 16 and the tampers 17 downwardly to tamp the cement in the mold chambers.

The pivot 23 may be extended in the form of a rock shaft, as shown in Fig. 1, and it may be mechanically driven through power applied to a pulley wheel 25 or any other suitable device.

As shown in Fig. 3 the adjacent vertical edges of the inner mold members 14 of one set are spaced from each other as at 14^a to provide an opening. This opening is normally covered by a slidable gate 26 mounted on the inner faces of the coördinate mold members 14-14, and access to these gates is had at the upper edges of the members 14 so that an attendant can by lifting the gates 26, that are opposite to each other with respect to a given scaffold frame 3, insert transverse tie or reinforcing means as the erection of the walls O and I proceed. As soon as the tie T has been placed the gates 26 are then again lowered and the filling of the cement continued.

In the operation of the device the jack posts having been erected with the slides 4 mounted thereon the lower edges of the several mold panels 12-12 14-14 are permitted to rest upon the ground or foundation and the cement fill is introduced up to such a height that when the lever arm 22 is thrown to lower the tampers 17 the latter will then bear on the top surfaces of the material in the mold chambers and the tampers can be operated a sufficient number of times to insure a proper tamping of this initial filling.

After that, material is continuously introduced evenly into the molds in horizontal layers and the tampers 17 continuously re-

ciprocated to pack the fill as it is introduced.

As the filling proceeds it is obvious that the constant increase in the height of the material results in a reaction on the tampers 17 and at suitable intervals the tampers can be forced solidly against the filling and then by rocking the lever 22-24 as by the rock shaft 23 or by the lever ends 24 this will result in a tendency of the reaction to cause the frame 3 to be lifted with the link 20 and the cross head 18 with the tampers 17 rest solidly on the bed of concrete.

Since the clamp device or ring 8 is arranged just above the upper end of the frame 3 the upward movement of this frame causes it to engage the clamp ring 8 of its respective post 2 and the ring will slide freely upwardly on the post a distance that will be determined by the angular movement of the lever 22-24 which is now utilized as a lifting means for the apparatus. Immediately the weight of the frame and apparatus is again thrown on to the lever 7, and the clamp ring 8 by release of the pressure on the link 20 by the lever 22 the clamp 8 then becomes automatically effective and locking itself holds the runner or slide 4 suspended by the link 6.

The arms 3 extend laterally a suitable distance to provide for the lateral adjustment of the pendent legs 11 thereon so as to vary the width between the mold sections 14-12. The upper parts 10 of the legs 11 may be bolted, screwed or otherwise fastened to the arms 3.

It is obvious that the device may be constructed and arranged to facilitate the molding of walls involving angles and openings and arranged and constructed to form walls of any thickness and desired exterior configuration.

Various modifications in the construction may be resorted to within the spirit of the invention and the scope of the appended claims:

1. Concrete mold apparatus for erecting concrete walls, comprising a standard; a frame slidably mounted on the standard and carrying mold forming sections; and automatic locking means for securing the frame to the standard and said means being readily movable with the frame in one direction; and tamping means mounted on the frame to be moved upwardly therewith.

2. Concrete mold apparatus for erecting concrete walls, comprising a standard; a frame slidably mounted on the standard and carrying mold forming sections; and automatic locking means for securing the frame to the standard and said means being readily movable with the frame in one direction; and tamping means mounted on the frame to be moved upwardly therewith; said tamping means operative as a jack to successively

lift the frame and its clamp during the erection of the wall by the filling of the mold chamber.

3. Concrete mold apparatus for erecting concrete walls, comprising a standard; a frame slidably mounted on the standard and carrying mold forming sections; and automatic locking means for securing the frame to the standard and said means being readily movable with the frame in one direction; and tamping means mounted on the frame to be moved upwardly therewith; said tamping means including a cross head slidably mounted on the standard and having a tamping rod with a tamper foot at its lower end, and operating connections between the cross head and means by which the cross head can be reciprocated to raise and lower the tampers.
4. Concrete mold apparatus for erecting concrete walls, comprising a standard; a frame slidably mounted on the standard and carrying mold forming sections; and automatic locking means for securing the frame to the standard and said means being readily movable with the frame in one direction; and tamping means mounted on the frame to be moved upwardly therewith; said tamping means including a cross head slidably mounted on the standard and having a tamping rod with a tamper foot at its lower end and operating connections between the cross head and means by which the cross head can be reciprocated to raise and lower the tampers; and by which when the tampers are supported on the filling the slidable frame can be elevated.
5. Apparatus for concurrently building parallel, vertical partitions to form a hollow wall, comprising a set of uprights; runners slidably mounted on the uprights

and having friction clamp means for locking the runner to the upright and adapted to permit free movement of the runners in one direction; sets of mold chambers forming means mounted on the runner of each standard; the said chamber forming means coöperating to provide a continuous filling chamber; and means for successively tamping filling charged into the mold chambers. 45 50

6. Apparatus for concurrently building parallel, vertical partitions to form a hollow wall, comprising a set of uprights; runners slidably mounted on the upright and having friction clamp means for locking the runner to the upright and adapted to permit free movement of the runners in one direction; sets of mold chamber-forming means mounted on the runner of each standard; the said chamber forming means coöperating to provide a continuous filling chamber; and means for successively tamping filling charged into the mold chambers; said means also operative to elevate the apparatus in successive stages as the filling of the chambers proceeds. 55 60 65

7. Concrete mold apparatus for erecting concrete walls, comprising a standard; a frame slidably mounted on the standard and carrying mold forming sections; and automatic locking means for securing the frame to the standard and said means being readily movable with the frame in one direction; and tamping means mounted on the frame to be moved upwardly therewith; and gate 70 75 forming means adapted to be opened to permit the introduction of reinforce or other members as the erection proceeds.

In testimony whereof I have signed my name to this specification.

EVAN B. HILLMAN.
